UNITED STATES PATENT OFFICE.

VICTOR LEFEBVRE AND TELESPHORE POLIQUIN, OF LOWELL, MASSACHUSETTS, ASSIGNORS OF ONE-THIRD TO ARTHUR LAVOIE, OF SAME PLACE.

CHIMNEY-CLEANER.

SPECIFICATION forming part of Letters Patent No. 614,874, dated November 29, 1898.

Application filed December 31, 1897. Serial No. 665,135. (No model.)

To all whom it may concern:

Be it known that we, VICTOR LEFEBVRE and TELESPHORE POLIQUIN, citizens of the Dominion of Canada, residing at Lowell, in the county of Middlesex, State of Massachusetts, have invented certain new and useful Improvements in Chimney-Cleaners; and we do hereby declare the following to be a full, clear, and exact description of the invention, 10 such as will enable others skilled in the art to which it appertains to make and use the same.

Our invention relates to improvements in chimney-cleaners.

The object of our invention is to provide 15 a device of this character in which the chimney can be readily cleaned without great trouble, the soot being placed in a position where it can be readily removed.

To this end our invention consists of the 20 improved construction and combination of parts hereinafter described and particularly pointed out in the claim.

In the drawings, in which similar letters of reference indicate similar parts in both views, 25 Figure 1 is a side elevation, partly in section, showing our improvement applied therein. Fig. 2 is a top plan view.

A designates a chimney having the usual central opening a and usual door or fireplace opening a' . An additional opening a^2 is provided at the bottom of the chimney, said opening being kept normally closed by means 30 of the door a^3 .

In the opening a and connected to one of the walls of the chimney near its top is mounted a pulley b , over which is adapted to pass a rope b' , extending downward to near the lower end of the chimney, where it passes over a similar pulley b^2 , said pulley b^2 being 35 provided with suitable means, such as a shaft

b^3 and handle b^4 , for rotating said pulley b^2 , said handle being located outside of the chimneys.

Connected to one end of the rope b' is a brush b^5 , formed preferably of steel, the periphery of the brush having the contour of the central opening a . The opposite end of the rope b' is provided with a turnbuckle b^6 , which is connected to the under side of the brush, thus forming a continuous rope or 45 chain, which when the handle b^4 is rotated will move the brush up or down the central opening and cleaning the chimney, the soot, &c., dropping to the bottom into a pan, if desired, from which it can be readily removed. 50

The advantages are obvious and include the readiness with which the chimney can be cleaned, and the mounting of the cleaner in the chimney permanently affording a means for cleaning the chimney at all times. 55

Having thus described our invention, what we claim as new is—

The combination with a chimney, having pulleys permanently mounted therein near the top and bottom; and means connected to 60 said lower pulley and operated from without said chimney, for rotating said pulley; a brush connected to said endless band; and a turnbuckle mounted in said endless band contiguous to said brush, to adjustably maintain the tension of said band, substantially as described. 65

In witness whereof we have hereunto set our hands in the presence of two witnesses.

VICTOR LEFEBVRE.
TELESPHORE POLIQUIN.
